UNITED STATES PATENT OFFICE.

ARCHIBALD D. SCOTT, OF JERSEY CITY, NEW JERSEY, ASSIGNEE TO VARLEY DUPLEX MAGNET COMPANY, OF JERSEY CITY, NEW JERSEY, A CORPORATION OF NEW JERSEY.

MANDREL FOR WINDING COILS.

1,167,723.

Specification of Letters Patent. Patented Jan. 11, 1916.

Original application filed September 27, 1910, Serial No. 584,040. Divided and this application filed September 8, 1912. Serial No. 718,812.

To all whom it may concern:

Be it known that I, ARCHIBALD D. SCOTT, a citizen of the United States, residing in Jersey City, in the county of Hudson and State of New Jersey, have invented certain new and useful Improvements in Mandrels for Winding Coils, of which the following is a specification.

My invention relates to new and useful improvements in winding mandrels upon which a strand or strands may be wound or coiled, and contemplates a mandrel which is so constructed that it may be readily collapsed within the winding so that the latter can be detached therefrom.

This application is a division of my pending application Serial Number 584,040, filed in the United States Patent Office September 27, 1910.

The invention consists in the novel construction and combination of parts to be fully described hereinafter, and the novelty of which will be particularly pointed out and distinctly claimed.

I have fully and clearly illustrated my invention in the accompanying drawings to be taken as a part of this specification and wherein:

Figure 1 is a view in end elevation of a mandrel embodying my invention. Fig. 2 is a vertical central section through the mandrel shown in Fig. 1; Fig. 3 is a view in end elevation of the filler blocks used in connection with the mandrel shown in Fig. 1; Fig. 4 is a detail view in section of a strand guide in connection with the mandrel shown in Figs. 1 to 3 included.

1 designates a winding spindle which may be driven in any suitable manner, and which has a threaded end onto which the hub 29 of a flange plate 30 is threaded, as clearly indicated in Fig. 2 of the drawings, said end plate 30 having a recess 31, at its central portion. Threaded into the hub 29, in alinement with the spindle 1 is a core-piece 33, which is conical in shape, the base of the cone being located within the recess 31 in the end plate, and the opposite end of said core-piece having a threaded shank 34 to receive an outer end plate 34^a, which is held in place on the conical portion of the core-piece between the end plates, is a plurality of filler blocks 36, shown as being four in

number, and each provided with an inclined 55 inner curved surface 37 to rest on the curved surface of the cone. The filler-blocks, in the embodiment shown, are each formed with outer surfaces 38 at right angles to each other, and the arrangement is such 60 that when the mandrel is assembled, the faces 38 of the filler-blocks align to provide a substantially rectangular body to receive the turns of the magnet winding, the corners of the filler-blocks constituting the 65 corners of the mandrel. The flange plates are each provided with a plurality of slots 39, through which tying bands may be passed in order to tie the layers of the winding together to prevent separation 70 thereof when the winding is removed from the mandrel.

In Fig. 2 one of the filler blocks is shown detachably secured to the inner end plate 30 by a bolt 40 so that said block constitutes 75 a bracket for the support of the winding when the end plate 34^a is removed. The outer flange plate 34^a is provided on its inner face, or that directed toward the winding space of the mandrel, with a recess 80 34^b which receives and holds the outer ends of the core-pieces 36. It will be noted that the filler-blocks at each end have projections 36^c to be seated in the recesses of the flange plates and that the receiving faces 85 of the filler-blocks are located laterally outside or beyond the walls of the recesses, as clearly indicated in Fig. 11 of the drawings. By this arrangement the end flanges 90 maintain the filler-blocks in proper position to give the desired conformation to the winding.

An important feature of this invention consists in providing the mandrel, whether it is designed to make round windings or 95 polysided windings, with means whereby the turns of the layers constituting a winding, will be arranged in regular form so that alternate layers are counterparts of each other throughout the entire winding, 100 the result being that I provide a completed article which is much more compact for a given weight of wire than any winding which has been produced heretofore, as far as I am aware, and which not only makes a 105 winding which is much more compact, but results in a great saving of wire, which, of course, in copper windings is important. In

order to arrive at this result, my invention broadly contemplates the provision of the mandrel with means whereby the first layer of the winding is laid between the flanges 5 of the mandrel with great precision, this winding serving then as a guide for the next layer and so on throughout the article produced. I have, up to the present time, contemplated and demonstrated the usefulness of several means for accomplishing this 10 result and I will now proceed to describe one of the same shown in the accompanying drawings.

Before proceeding with a detail description, I believe the method will be better understood if it is borne in mind that the procedure is based on the fact that the distance from the flange plate of any wire which is the nearest one of its layer to the 15 plate must be either zero or one-half the diameter of the strand, in order that the arrangement of strands in layers will be such that it is repeated as layer after layer is wound on the core. In order to accomplish 20 this result I employ a device which makes the first turn take a determined course, so that the subsequent turns, when laid against the same, will take a corresponding course across the face of the mandrel. In the present embodiment of the invention I employ 25 a guide or projection secured to the mandrel and extending beyond the receiving face thereof, a distance equal to the diameter of the wire and of a thickness equal to one-half the diameter of the wire, said device being arranged flush against one of the end 30 plates. This device may take a number of forms but I prefer to employ a pin 70 seated in a recess 71, in the end of two of the adjacent 35 filler blocks, said recesses being located at the corners of the blocks and said pin having an enlarged head 72 which abuts the end plate 34, and projects beyond the 40 face of the mandrel between the end plates, said head having a rounded surface as at 45 74, so that it practically constitutes, in effect, a half strand of wire laid against the end plate. The flange or head 72, projects beyond the receiving surface of the mandrel 50 a distance substantially equal to the diameter of the wire being wound, and is of such thickness that its inner face, or the face away from the head of the mandrel, takes 55 position away from said head a distance equal to one-half the diameter of the wire being wound. When the wire is then wound on the mandrel, it will be held away from the end plate a distance equal to one-half its diameter by the projecting head of this 60 pin, at two of the corners of the mandrel, but will lay against the end plate at the other corners of the mandrel. As the coil is wound, all of the succeeding turns of the first layer will be correspondingly laid and 65 the turns of the second layer will be guided

by the turns of the first layer, the final turn resting in the groove formed by the head 74, and the next adjacent turn of the first layer, 75, the head 74 preventing the next to last turn of the second layer from forcing 70 the end turn of the first layer away from the second turn of the first layer.

It will be understood that interchangeable guide devices are employed, the guide device being selected according to the diameter of wire to be wound. 75

The filler blocks for the mandrel may each be formed with a longitudinal rabbet 76, which when they are assembled coincide to form grooves longitudinally of the mandrel through which binding strips may be passed between the winding and the mandrel.

What I claim and desire to secure by United States Letters Patent is: 85

1. A winding mandrel comprising a receiving body provided with end flanges and having means to cause the turns of a layer to lie parallel with the direction of rotation over a determined area of the mandrel, and oblique to the direction of rotation through another area of the mandrel, said means comprising guiding devices spaced from each other about the mandrel and located at the juncture of an end flange with the body, 90 said guiding devices projecting inward from the flange equal distances and formed to permit the endmost turn of a subsequent layer to take position against an end flange. 95

2. A winding mandrel, an end flange or head therefor, and a guiding device located at the angle between the receiving surface of the mandrel and the flange, said device projecting outward beyond the receiving surface a distance substantially equal to the 100 diameter of the wire and having a guiding face, and said device projecting from the head lengthwise of the mandrel a distance substantially equal to one-half the diameter 105 of the wire. 110

3. A winding mandrel comprising a poly-sided receiving body provided with end flanges and having means to cause the turns of a layer to lie parallel with the direction of rotation over a determined area of the 115 mandrel and oblique to the direction of rotation through another area of the mandrel, said means comprising guiding devices spaced from each other about the mandrel and located respectively at the meeting points of sides thereof and at the juncture of an end flange with the body, said guiding devices projecting inward from the flange equal distances longitudinally of the body. 120

4. A winding mandrel, a head for the 125 mandrel, and means on the mandrel for guiding the initial coil laid on the mandrel away from said head, said means having a convexly curved face adapted to form with an adjacent strand a guide groove for a turn 130

- of a superposed layer, and being so formed that the endmost turn of the said subsequent layer may take position against the head.
5. A winding mandrel having a socket in an end face thereof and extending lengthwise of the mandrel, a guiding device consisting of a pin seated in the socket and having a part extending laterally from the pin and projecting beyond the receiving face of the mandrel.
6. A winding mandrel having a socket in an end face thereof, a guiding device consisting of a pin removably seated in the socket and having a part extending laterally from the pin and projecting beyond the receiving face of the mandrel, and a head for the mandrel, said head holding the guiding device in place.
7. A winding mandrel, an end flange or head therefor, and a guiding device located at the angle between the receiving surface of the mandrel and the flange, said device projecting radially of the mandrel a distance substantially equal to the diameter of a strand and lengthwise of the mandrel a distance substantially equal to one-half the diameter of the strand, and having a guiding face adapted to form with an adjacent strand a guide groove for a turn of a superposed layer, and so formed that the endmost turn of the said subsequent layer may take position against the head.
8. A winding mandrel having a recess in the end face thereof, and a strand guiding pin removably seated in said recess and having a head projecting laterally beyond the receiving surface of the mandrel, and formed to constitute with an adjacent strand a guide groove for a superposed layer.
9. A winding mandrel having a recess in the end thereof, a pin seated in said recess and having a head projecting laterally beyond the receiving surface of the mandrel a distance equal to the diameter of a wire to be wound, and a thickness substantially equal to one-half the diameter of a wire to be wound, and an end plate for the mandrel abutting the head of said pin.
10. A polysided mandrel having a recess in the end face thereof adjacent the point of union of two of its sides, and a guiding device located in said recess and having a part projecting beyond the receiving surface of the mandrel at the corner formed by said meeting sides and forming with an adjacent strand a guide groove for the end turn of a superposed layer.
11. A polysided mandrel having end plates having faces at right-angles to the receiving surface of the mandrel, a projection at each of two adjacent corners of the mandrel against an end plate and projecting radially beyond the receiving surface of the mandrel a distance substantially equal to the diameter of a wire to be wound, and inwardly from the end plate a distance substantially equal to one-half the diameter of a wire to be wound, the remainder of the receiving surface of the mandrel being free and unobstructed.
12. A winding mandrel comprising a polysided body composed of a plurality of filler-blocks each of which has a corner forming a corner of the mandrel, heads for the mandrel, and a strand guiding device located at each of two adjacent corners of the mandrel, and adjacent one of the heads, said devices projecting radially from the receiving surface of the mandrel a distance approximately equal to the diameter of the strand to be wound and projecting lengthwise of the mandrel away from the head a distance approximately equal to one-half the diameter of said strand.
- In testimony whereof I have hereunto signed my name in the presence of two subscribing witnesses.
